UNITED STATES PATENT OFFICE

GUSTAVE A. UNGAR, OF PELHAM MANOR, NEW YORK

MANUFACTURE OF CORRUGATED PAPER BOX BLANKS

Application filed April 1, 1930. Serial No. 440,718.

My invention relates to machines for creasing and folding so-called corrugated cardboard such as is commonly used in making boxes or containers. One of the objects is to provide a machine for automatically forming and creasing a blank. Specifically I have sought to provide mechanism for cutting or slotting a blank and then creasing it accurately in line with the slots. The material is of such a character that in order to fold it to form a box it is necessary to crush the material quite deeply. This peculiarity of the material makes it difficult to crease by the use of rolls, that is, with sufficient accuracy for practical high speed operation. I have accordingly provided jaws capable of grasping the material and automatically applying the pressure necessary for crushing the cellular structure. For commercial production high speed is of course desirable. I have therefore combined the creasing mechanism with rotary shears or cutters and so designed the creasing mechanism as to permit continuous operation.

In the preferred form as herein illustrated the blanks are automatically slotted and trimmed at the sides by rotary shears of a suitable character.

The creasing mechanism broadly considered consists of a series of rotating jaws into which the slotted blanks are fed.

These jaws are arranged in pairs and one member of each pair serves as a traveling abutment against which the material is crushed along the desired lines by the complementary punch member. These jaws are brought into action consecutively so as to handle the blanks as they come from the shearing or cutting mechanism and deliver the slotted and creased blanks to traveling means by which blanks may be folded ready for gluing.

In order that the machine may handle blanks of different sizes and slot and crease them in the desired manner, various parts of the machine are preferably made adjustable. I have also provided means for adjusting the members of the jaws so that stock of different thicknesses may be handled in the same machine.

In order to illustrate the principles of the

invention I have herein shown and will hereinafter describe one form of mechanism.

Fig. 1 is a side view showing some of the parts of the machine.

Fig. 2 is a plan view and horizontal section 55 of the machine.

Fig. 3 is an end view and transverse section on the plane of the line 3—3 of Fig. 1.

Fig. 4 is a transverse section on the plane 60 of the line 4a—4b of Fig. 1.

Fig. 5 is a fragmentary transverse section 65 on the plane of the line 5—5 of Fig. 1.

Fig. 6 is a fragmentary transverse section on the plane of the line 6a and 6b of Fig. 1.

Fig. 7 is a vertical sectional view showing 65 the creasing mechanism with one pair of jaws in the act of creasing a blank and another pair of jaws shown delivering the creased blank.

Fig. 8 is a vertical sectional view showing 70 the creasing mechanism with the jaws in a different position, and showing the stationary cam for actuating the opening and closing movement of the abutment or relatively stationary jaws.

Fig. 9 is a vertical sectional view of the 75 creasing mechanism showing the stationary cam for actuating the punch members of the jaws.

Fig. 10 is a side view showing one pair of 80 creasing jaws on a larger scale with the means for applying pressure.

Fig. 11 is a transverse section showing the supports for one pair of jaws, the section being on the plane of the line 11—11 of 85 Fig. 10.

Fig. 12 is a transverse section of the creasing jaws on the plane of the line 12—12 of Fig. 10.

The cardboard sheet 20 which is to form 90 the box blank is fed into the machine in any suitable manner. The shafts 21, 22 are provided with cutters such as 23 and 24 for trimming the edges and intermediate cutters such as 25, 26 and 27 for cutting slots in the 95 trimmed blank. These cutters are of course arranged in upper and lower pairs for providing the necessary shearing action and the blank as it leaves the cutters has a general 100 shape, as shown at 28 in Fig. 2.

The blank is to be creased along the lines corresponding to the slots 25', 26' and 27'. The slotted blank after it leaves the cutters is picked up by traveling chains 30 which carry it into the guides 31 and 32. The roller 33 presses downwardly by gravity and/or by springs to hold the blank against the upper surface of the chain conveyor. The stock is supported by rollers 34 beneath the roller 33. The roller 34 is mounted on a shaft with the sprocket 35 which drives the chain conveyor. The chain is provided with projecting fingers or lugs 36 at intervals to engage the successive blanks. The chain 30 also passes around the sprocket 37 on the shaft 38 through which power is applied to the chain. A second shaft 39 is arranged adjacent the creasing mechanism and chains 40 which travel on sprockets such as 41 and 42 serve to take the blanks from the chain 30 and deliver them in a direction substantially radial to the axis of the creasing mechanism which is mounted on the shaft 43. A stop 44 is hinged at 45 and provided with a spring 46 which holds it yieldingly in the position shown in Fig. 1 so that when a blank is fed toward the creasing mechanism by the chains 40 its movement forward will be checked at the proper point for engagement by the creasing jaws.

Each pair of jaws has an abutment member 50 and a creasing member 51, the gripping surfaces of which are designed to most effectively crush the material which the machine is to handle. In this case the abutment member has a flat faced die 52 and the creasing member has a V-shaped punch member 53. These punch and die members are preferably detachably connected to their respective carrier members, for instance, by machine screws such as 54 and 55.

The abutment jaw 50 is supported on an eccentric 56 on the sleeve 57 on the shaft 58. The shaft is either angular in cross section or provided with a spline or key to permit the sleeve 57 to slide longitudinally upon it but rotate with it. The arm 59 is keyed on to the sleeve 57 and has its outer end engaged in a groove in the jaw member 50 with a spring 60 interposed as shown in Fig. 12.

The companion or creasing jaw member 51 is similarly supported on an eccentric 61 on the sleeve 62 on shaft 63. The arm 64 is keyed on the sleeve 62 and has its outer end engaged in the groove 65 of the creasing jaw member 51 with a spring 66 interposed.

The shafts 58 and 63 are supported in heads 70 and 71 on opposite ends of the shaft 43.

Sleeves 57 and 62 are supported in discs 72 and 73 which are mounted on the shaft 43 and held together by bolts 74. The discs are keyed on the shaft as at 75.

The rotating jaw carrier is supported by the standards or pillars 80, 81, on opposite sides of the machine. The main shaft is

made up of three sections together with connecting discs or spiders. The main section 43 above mentioned directly supports the discs to which the creasing jaws are hinged. The end sections 82 and 83 are supported in suitable bearings in the standards 80 and 81 respectively. The discs 84 and 85 are keyed to the inner ends of the stub sections 82 and 83 and connected by bolts such as 86 and 87 to the respective heads or disc-like members 70 and 71.

The shaft 58 has one end rotatably mounted in the head 70. The other end is rotatably supported in a sleeve 88 which extends through the head 71 and the disc 85. On the extreme end of the shaft 58 is mounted an arm 89 which carries a roller 90 which travels in a groove in the cam 91 which is fixed to the standard 81.

Similarly the shaft 63 has one end rotatably mounted in the head 71 and the other end rotatably supported in the heads 70 and 84 and provided with an arm 92 which has the roller 93 guided in the cam member 94 which is secured to the standard 80, for instance, by bolts 95.

Figs. 7, 8 and 9 show various relative positions of the creasing jaws as brought about automatically and consecutively by the action of the cams 91 and 94 upon the various shafts 58 and 63.

In Fig. 7 it will be seen that the jaw member 50' has its abutment surface substantially radial to the carrier so that as the carrier rotates anti-clockwise this jaw member 50' will pick up the blank 28'. The outer end of the jaw member 51' is spread apart from the complementary abutment jaw member 50' in order to leave room between the jaws for the entry of the blank 28' since the blanks are being continuously fed into the creasing member which is continuously rotating. The jaw member 51' is moved to the position shown in Fig. 7 by the roller 93' in the groove of the cam 94. The shape of this cam groove is such as to automatically move the jaw member 51' into the position of the jaw member 51'' when the jaw members are substantially horizontal as shown in Fig. 7 at which point the creasing action takes place.

It is possible by this mechanism thus far described to crease the blanks in this manner but I prefer to provide a supplementary power device to give a final pressure to the jaws. For this purpose I provide a rotating member 100 which is mounted on a shaft 101 and provided with rollers 102 and 103 which in effect form two teeth of a gear member and coact with the cam-like portions 104 and 105 at the ends of the creasing jaws 51 and 50 respectively when the parts are in the position shown at the right in Fig. 10 and shown in Fig. 7. Fig. 9 shows the start of the engagement of one cam portion 104 with the roller 102. As the jaw carrier rotates anti-

clockwise and the closing device rotates clockwise to the position shown in Fig. 7, the cam member 105 is engaged by the roller 103 and substantial gripping pressure is applied to put the desired crease in the blank.

It will be seen that this closing movement of the jaws 50 and 51 is not transmitted to the actuating cams 91 and 94 because the jaw members have a limited freedom of movement with respect to the arms 59 and 64 which are mounted directly on the shafts 58 and 63 which carry the cam rollers.

It will be obvious from what has just been stated that the extent of the closing movement of the creasing jaws can be readily adjusted either by moving the closing device 110 toward the jaw carrier or by moving the jaws themselves longitudinally toward the closing device. I prefer to perform the latter operation and at the same time move the inner ends of the jaws toward each other by the simple expedient of rotating the eccentrics 56 and 61 in opposite directions. This is accomplished by providing gears 106 and 106' on the eccentrics 56 and 61 respectively, which are in mesh with each other and driven by a pinion 107 on shaft 108 which is rotatably supported in the heads 70 and 71 above mentioned. One end of the shaft 108 is provided with a gear 109 which meshes with an idler gear 110 which in turn is driven by a gear 111 on the shaft 112 which may be actuated by suitable mechanism such as the hand wheel 113. (See Fig. 2.) By rotating the hand wheel 113 and the gear train above mentioned the shaft 108 is rotated, which in turn rotates the gears 107, 106, 106' and the attached eccentrics 56, and 61 respectively, thus moving the two creasing jaws in accordance with the setting of the eccentrics and closing their hinged ends toward each other at the same time that they are moved longitudinally toward the closing rolls 102 and 103.

This action results in the closing of the jaws toward each other while maintaining their punch and die faces parallel so as to produce a crease uniform in depth from one edge to the other of the blank and regardless of the thickness of the blank.

As the creasing jaw carrier and the closing rolls continue to rotate the jaws are disengaged or freed from the closing device as shown in Fig. 8. As the jaw carrier continues to rotate, the creased blanks are carried upwardly and then downwardly to the left until they reach the position at the left of Fig. 7, where the blank 28" is engaged by the chain 120 which travels on sprockets 121 and 122. Intermediate the sprockets the blank is supported in its central portion by a number of guides or supports 123 and 124 and 125. The chain is preferably provided with lugs 126 for engaging the rear edge of the blank.

The construction as shown not only produces a slotted and creased blank but also folds the creased blank ready for gluing. For this purpose I provide stationary inclined bending abutments 130 and 131 at opposite sides of the creasing jaws so that the blank is bent along the creases nearest to the outer edges of the blank by virtue of the movement of the creasing jaws as they move the blank downward between the inclined abutments 130 and 131. As soon as this initial creasing action is completed as just described, the abutment jaws 50a are retracted from the position shown in Fig. 7 to that shown in Fig. 8 so as to clear the blank 28" and allow it to be moved to the left by the conveyor chain 120.

This retracting movement of the abutment jaw 50a is performed by the cam 91 and the roller 90 on the shaft of the abutment arm in accordance with the principles heretofore described.

As the initially creased blank 28a moves to the left with the conveyor 120 it is discharged on to the conveyor 132 which travels on the sprockets 133 and 134. The central portion of the blank is then supported by the members 123, 124 and 125. As the blank moves forward it passes beneath the roller 135' and 135 by which it is held down while the lateral bending rollers 136 and 137 fold the edges of the blank into the position shown in Fig. 5. As the partially folded blank continues in this movement it is engaged by other rollers such as 138 and 139 to close the edges gradually and complete the folding operation preparatory to gluing in any suitable manner.

In the form shown power is applied to drive the various parts automatically, for instance, by means of the motor 140 as shown in Figs. 2 and 3. The cutting rolls are driven by chain 141. The shaft 101 for rotating the closing or supplementary power device is driven by a chain 142. The shaft 101 also has a gear 143 meshing with gear 144 on the countershaft 145. The countershaft has a sprocket 146 for driving the chain 147 which drives the sprocket 148 on the end of the main shaft of the jaw carrier. The shaft 145 also has a sprocket 150 which drives the sprocket 151 through the chain 152.

The sprocket 151 is on the shaft 38 which carries the sprocket 41 and drives the chain 40 for feeding the blanks upwardly toward the jaw carrier. This shaft 38 also carries a sprocket 37 which drives the chain 30 which feeds the stock from the cutters to the pick-up chain 40.

The sprockets 122 and 133 are mounted on the shaft 154 which has a sprocket 155 on its outer end connected by chain 156 with sprocket 157 on shaft 38.

In order to permit proper timing of the chains 30 and 40 with respect to blanks of different widths, the sprockets 151 and 157

above mentioned are rotatably mounted with respect to the shaft 38 and connected for rotation by means of a clutch 160 which may be actuated by a lever 161. By disconnecting 5 clutch 160 from the corresponding clutch teeth on the hub of the sprocket 151, the shaft 38 and sprockets 37 and 41 may be rotated so as to move the chains 40 and 30 and bring 10 the blank properly with respect to the feed of the chain 30 and the timing action of the creasing jaws.

It will be understood of course that the cutters 23 to 27 will be of suitable diameter to 15 feed and cut the selected blanks and that their rotative position with respect to the feeding of the chains 30 and 40 will be adjusted correspondingly.

In order to handle blanks of different sizes 20 requiring slotting and creasing according to different spacings, it is desirable that the various parts of the machine be made laterally adjustable.

The slotting cutters themselves may be 25 adjusted longitudinally on the cutting shaft 21 in any suitable manner so as to trim the blank at the proper width and cut the slots according to the proper lateral spacing. The lateral guides 31 and 32 are supported by bars 30 170 and 171 (see Figs. 1, 2 and 3), which are slidably mounted in the frame and may be clamped as for instance by set screw 172. For convenience in assembling and adjusting the yielding abutment plates 44 are carried 35 by the inner ends of the guides 31 and 32 respectively, so that they are adjusted back and forth to correspond with the proper width of the blank.

For the purpose of adjusting the feed-in 40 and pick-up chains their shafts and sprockets are supported by sub-frames or brackets 175 which are mounted to slide on cross guides 176 and may be adjusted by screws 177 which have a threaded engagement in the base of 45 the brackets so that by rotating the screws 177 and 177' the chain supporting brackets may be moved outward or inward as occasion may require and independently of each other.

The closing devices which are slidably 50 mounted on the shaft 101 are provided with bearing brackets 180, 180a and 180b. The central bracket 180a is stationary and in line with the approximate center of the machine and therefore need not be adjustable. The 55 outer brackets 180 and 180b are laterally adjustable by screws 181 and 182 respectively, which are supported in the bearing brackets 183 and 184 which constitute parts of the frame of the machine.

60 The jaw carrying discs are adjustable laterally by screws 185 and 186 which are rotatably supported in the heads 70 and 71 of the carrier. The screw 185 has on one end a gear 187 which meshes with a gear 188 on 65 the shaft 189 and the latter has a suitable

mechanism such as a hand wheel 190 for rotating it and thus adjusting the outer jaw carrying disc by a well known screw and nut principle. The other screw shaft 186 has a gear 191 on one end which meshes with 70 a gear 192 on the sleeve or hollow shaft 193 actuated by a suitable mechanism such as a hand wheel 194.

The outer units of the feed-out and folding mechanism are similarly adjustable. In 75 this case the bending abutments 130 and 131 are carried by sub-frame members such as 195 and 196.

These two frame members 195 and 196 are mounted on transverse guide beams 197 80 and they may be moved back and forth laterally, for instance by screws 198 and 199. These frame members 195 and 196 also carry with them all of the sprockets for the feed-out chains and also the supports 124 and 125 85 as well as the folding rollers. The holding-down rollers 135 are carried by brackets 200 which are supported on the transverse guide rods 201 so that the rollers may be adjusted transversely independently of each other. 90 The folding rollers 136, 137, 138 and 139 are supported by brackets such as 204 to permit them to be longitudinally adjusted on the frame member 195. They may also be adjustable with respect to the inclination of 95 their axes by being pivotally mounted as shown at 205 in Fig. 5.

It should be understood that all the lateral 100 adjustments pertaining to each of the outer creases may be simultaneously effected by suitable connecting mechanism (not shown).

It will be seen from the foregoing that we have provided automatically and continuously operating mechanism for consecutively treating a sheet of corrugated paper or 105 the like, first trimming and slotting it at the proper points, next feeding it, then creasing the blanks accurately in alignment with the previously formed slots, then discharging it from the creasing mechanism, and then folding the blank along the creased lines and discharging it folded ready for gluing. Obviously the latter operation might be effected on the same machine or in a subsequent 110 operation.

As above pointed out, parts of the above 115 mechanism are adjustable laterally to handle blanks for different sizes of boxes. It is also adapted to handle various thicknesses of stock.

All of the adjustments, as above pointed out, are of such a nature as to be simply performed. The nature of the creasing mechanism is such that it can be performed on various kinds of stock and regardless of the thickness or the cellular character. The latter feature is of great importance because of the irregularity and peculiar characteristic of corrugated paper or board, which characteristic makes it extremely difficult to han- 125 130 135

dle by any of the previously known mechanisms. The mechanism is also capable of operation continuously at a high rate of speed and with accuracy.

5. I claim:

1. In a corrugated paper machine cutters for slotting a blank, jaws for creasing the blanks as they leave the cutters and means for automatically folding the creased blanks, means for automatically transferring the blanks from each element to the next and means for continuously moving the creasing jaws.

15. A slotting and creasing machine comprising slotting rolls having cutters, rollers for engaging the blanks as they leave the slotting rolls, conveyor chains having lugs for engaging the blanks and creasing jaws actuated in alinement with the slotting cutters.

20. 3. A slotting and creasing machine comprising, slotting rolls having adjustable cutters, creasing jaws adjustable in alinement with the cutters and means for continuously actuating the cutters and creasing jaws.

25. 4. A corrugated paper machine means for slotting a blank and continuously movable jaws for creasing the blank in alinement with the slots while it moves.

30. 5. In a corrugated paper creasing machine, a continuously rotating carrier having a pair of creasing jaws and continuously movable means for feeding blanks into the jaws.

35. 6. In a creasing machine, a continuously rotating carrier having a number of pairs of creasing jaws and means for adjusting one pair toward and from another pair.

40. 7. In a creasing machine, a pair of hinged creasing jaws and a rotating member having shoulders for engaging said jaws for creasing.

45. 8. In a creasing machine, a pair of rotating and hinged jaws having eccentric bearings and means for rotating the bearings to adjust the creasing action.

50. 9. In a creasing machine, a continuously rotatable carrier having a head with a cam, a pair of creasing jaws carried by the carrier and having an actuator coacting with said cam.

55. 10. In a creasing machine, a continuously rotating carrier, a number of pairs of creasing jaws carried thereby, and means for swinging one jaw of each pair relative to its companion jaw.

60. 11. In a creasing machine, a rotating carrier, a number of pairs of creasing jaws carried thereby, means for moving one jaw of each pair in advance of its companion jaw through part of a revolution and means for moving the other jaw independently of the first mentioned jaw through another part of the revolution.

65. 12. Creasing mechanism comprising a rotating carrier having hinged jaws, means for feeding blanks to the jaws and a yielding

abutment for stopping the blank as it is fed between the jaws.

13. Creasing mechanism comprising a pair of jaws, an adjustable eccentric supporting one end of each jaw, and a closing device co-acting with the opposite ends of the jaws.

14. Creasing mechanism comprising a rotating carrier, jaws hinged thereto, a stationary cam and connectors between one jaw and said cam.

15. Creasing mechanism comprising a rotatable carrier having heads at opposite ends, shafts carried by said heads, discs slidably mounted on said carrier and creasing jaws mounted on said discs and connected to said shafts.

16. The combination of a continuously rotating carrier having hinged creasing jaws, stationary abutments for engaging the edges of blanks as they are delivered by the jaws and means for folding the bent edges of the blank.

17. A creasing carrier having pairs of creasing jaws and stationary cams at opposite ends of the carrier connected to the jaws for actuating them independently.

18. In a box machine, slotting cutters, a feed chain leading therefrom, a second feed chain for receiving a blank from the first chain, creasing means in alinement with the slotting cutters and means for adjusting the feed of one chain with respect to the other chain.

19. In a creasing machine, a rotating carrier, a pair of jaws pivoted to said carrier and extending away from the axis of the carrier, two cams, and means of connection between said cams and said jaws for independently moving the jaws while the carrier rotates.

20. In a creasing machine, a carrier, a pair of creasing jaws pivoted to the carrier, eccentrics for moving the pivoted ends of the jaws toward and from each other, and means for pressing the outer ends of the jaws toward each other.

GUSTAVE A. UNGAR.
